UNITED STATES PATENT OFFICE.

ARTHUR A. MCRAE, OF ATTLEBORO, MASSACHUSETTS, ASSIGNOR TO
MCRAE AND KEELER, OF SAME PLACE.

DESIGN FOR A SPRING-SUPPORT FOR HAT-PIN ORNAMENTS.

SPECIFICATION forming part of Design No. 34,310, dated April 2, 1901.

Application filed February 7, 1901. Serial No. 46,449. Term of patent 7 years.

To all whom it may concern:

Be it known that I, ARTHUR A. MCRAE, a citizen of the United States, residing at Attleboro, in the county of Bristol and State of Massachusetts, have invented and produced a new and original Design for a Spring-Support for Hat-Pin Ornaments, of which the following is a specification, reference being had to the accompanying drawings, forming part thereof.

Figure 1 is a side view of my newly-designed spring-support for the ornament forming the crown or finial of a hat-pin. Fig. 2 is an end view, on an enlarged scale, of the spring-support. Fig. 3 is a sectional view of the spring-support.

Hat-pins are usually provided with ornamental heads. These are frequently jeweled, and it is desirable to give to these heads a spring-support whereby a tremulous movement is imparted to the head, so that the jewels or facets of the head may reflect constantly-varying lights or colors.

As shown in the drawings, the leading and

material feature of my design consists in ²⁵ the goblet-shaped outline of the spiral wire spring. The stem-like portion of smaller diameter is usually connected to the pin, and the cup-shaped end of larger diameter forms the base or support of the ornamental head. ³⁰

The vertical outline of the spring-support forms a double or reverse curve by the union of the concave outline of the stem with the convex outline of the cup portion of the spring-support.

Having thus described my invention, what I claim as new, and desire to secure by Letters Patent, is—

The design for the spring-support for hat-pin ornaments as herein shown and described.

In testimony whereof I have signed my name to this specification in the presence of two subscribing witnesses.

ARTHUR A. MCRAE.
